(57) **CLAIM**

The ornamental design for a fan with light as shown and described.

DESCRIPTION

FIG. 1 is a front bottom left perspective view of a first embodiment of a fan with light showing the design;

FIG. 2 is a front side view thereof;

FIG. 3 is a rear side view thereof;

FIG. 4 is a right side view thereof;

FIG. 5 is a left side view thereof;

FIG. 6 is a bottom plan view thereof;

FIG. 7 is a top plan view thereof;

FIG. 8 is a front bottom left perspective view of a second embodiment of a fan with light showing the design;

FIG. 9 is a front side view thereof;

FIG. 10 is a rear side view thereof;

FIG. 11 is a right side view thereof;

FIG. 12 is a left side view thereof;

FIG. 13 is a bottom plan view thereof; and,

FIG. 14 is a top plan view thereof.

(Continued)

The broken lines represent portions of the fan with light that form no part of the claimed design.

1 Claim, 10 Drawing Sheets
